United States Patent Office

Des. 177,798
Patented May 29, 1956

177,798

TOY WHIRLER OR SIMILAR ARTICLE

Francis J. Delaney, Fresno, Calif.

Application March 7, 1955, Serial No. 34,895

Term of patent 14 years

(Cl. D34—15)

FIG. 1.

FIG. 2.

FIG. 3.

FIG. 4.

Fig. 1 is a top plan view of a toy whirler or similar article, showing my new design;

Fig. 2 is a front elevational view thereof;

Fig. 3 is a rear elevational view thereof; and

Fig. 4 is a side elevational view thereof, the opposite side having substantially the same appearance.

I claim:

The ornamental design for a toy whirler or similar article, as shown and described.
